CLAIM

The ornamental design for a cooktop cover, as shown and described.

DESCRIPTION

FIG. 1 is an upper perspective view of a cooktop cover design;

FIG. 2 is a front view of the design of FIG. 1;

FIG. 3 is a rear view of the design of FIG. 1;

FIG. 4 is a right side view of the design of FIG. 1;

FIG. 5 is a left side view of the design of FIG. 1;

FIG. 6 is a top view of the design of FIG. 1; and,

FIG. 7 is a bottom view of the design of FIG. 1.

The broken line disclosure represents unclaimed portions of the cooktop cover in which the design is embodied.

1 Claim, 5 Drawing Sheets(56)
